UNITED STATES PATENT OFFICE.

JOSEPH J. SCHULTZ, OF BROOKLYN, NEW YORK.

LOOSE-LEAF BINDER.

Application filed November 10, 1922, Serial No. 600,090. Renewed January 10, 1925.

To all whom it may concern:

Be it known that I, JOSEPH J. SCHULTZ, a citizen of the United States, residing in Brooklyn, in the county of Kings and State of New York, have invented certain new and useful Improvements in Loose-Leaf Binders, of which the following is a specification.

This invention relates to a loose-leaf binder for removably holding separate pieces of material, such as maps, samples of paper, cloth, etc.

One object of the invention is to provide such a device that will permit of the easy and quick removal of any one of the pieces held, or the easy and quick insertion of an additional piece.

Another object of the invention is to provide means whereby the separate pieces or leaves may be adjustably held firmly together along their inserted edges and thereby injury to the leaves may be prevented while they are being turned.

Other objects of the invention are to improve generally the simplicity and efficiency of such devices and to provide a binder of this kind which is durable, economical to manufacture, and which will not get out of order.

The inventive features for the accomplishment of these and other objects are embodied in an improved loose-leaf binder, which, briefly stated, comprises two side members or covers, leaf-supporting studs hingedly connected to said side members, leaf-compressing bars loosely mounted on said studs, and means for adjusting said compressing bars.

Other objects of the invention will appear as the description proceeds, and while herein details of the invention are described, the invention is not limited to these, since many and various changes may be made without departing from the scope of the invention as claimed.

In the accompanying drawings, showing by way of example two of many possible embodiments of the invention—

Fig. 1 is a perspective view of my binder, with the leaves removed.

Fig. 2 is an enlarged sectional view of one form of my device, taken at one of the studs of Fig. 1.

Fig. 3 is an enlarged plan view of my device, also with the leaves removed.

Fig. 4 is an enlarged sectional view, sim-

ilar to Fig. 2, of another form of adjusting means.

As shown in Figs. 1, 2 and 3, one form of my binder comprises two side members 60 10 joined together by a curved back portion 11 flexibly connected to the inner edges of said side members and forming a leaf-binding mechanism space 12. Flat metallic members 17 are attached to the 65 inner edges of said side members having their free edges rolled into tubular form, as at 18, Fig. 1, and extending into said space 12. The tubular portions of connecting members 17 have a plurality of cut-out 70 places 19 into which the ends of threaded studs 20 are adapted to be inserted, with holes 22 in the ends of said studs 20 in alignment with the tubular portions of members 17 for receiving retaining rods 75 26 insertable into the said tubular portions 18 and passing through holes 22, thereby hingedly connecting members 17 and 20.

On the studs 20 are mounted two flat bars 30, between which are clamped 80 leaves 31 mounted on studs 20, the bars 30 being adjusted to the leaves by means of a nut 32 on each threaded end of the leaf-supporting studs 20.

When it is desired to remove or insert 85 a leaf, the retaining rod 26 on the side of the bundle from which a leaf is to be added or taken is withdrawn, the nuts 31, if any, on that side unscrewed off studs 20, and the compressing bar 30 lifted off, which leaves 90 the studs free for the addition or removal of a leaf.

In Fig. 4 there is shown another form of leaf-compressing adjusting means, in which the leaf-supporting stud 20' is threaded 95 from end to end and has two nuts 32' on each stud, instead of one as shown in Fig. 3, which permits of positioning the leaves at different places along the studs 20', or the removal of the leaves from the side 100 members as a whole, without the leaves becoming disarranged. In Fig. 4 the leaves 31' are shown, as at 33, cut out from the stud hole to the back edge thereof to form a notch, while the leaves 31 are shown at 105 34 in Fig. 2 as having only a stud hole. While the stud holes and notches are not shown as applied interchangeably to both forms of studs, the invention is not so limited.

It is obvious that when it is desired to add or remove a leaf of the notched type,

it is only necessary to relieve the pressure on bars 30 or 30' by unscrewing the nuts 32 or 32', thus permitting of the pushing in or pulling out of a leaf.

5. I claim:

1. In combination, side members; studs adapted to receive a pack of loose leaves thereon, each stud being pivotally connected at its respective ends to said members, the 10 pivot points of the studs adjacent each said member being alined, and compressing members received on said studs between said pack and the pivotal connection.

2. In combination, side members; threaded studs adapted to receive a pack of loose leaves, each stud being detachably pivotally connected at its respective ends to said members, the pivot points of the studs adjacent each side member being alined, and nuts 20 received on said studs between said pack and the pivotal connection.

3. In combination, side cover members; hinge members fast on the side members; rods longitudinally slidably received in said 25 hinge members; threaded studs adapted to receive a pack of loose leaves and provided with transverse end holes pivotally received on said rods; compressing members loosely received on said studs for engagement with the pack; and nuts on said studs between one of said compressing members and the adjacent end holes for causing said compressing members to clamp the leaves.

4. In combination, side members; rods 35 thereon; threaded studs adapted to receive loose leaves and detachably pivotally connected directly to said rods; and nuts received on said studs on both sides of the leaves between said leaves and rods.

40 5. In combination, side members; threaded studs adapted to receive loose leaves and provided with transverse holes; means detachably connecting to said members and passing through said holes for retaining the 45 studs; and nuts received on said studs between said leaves and the holes, and removable past the holes.

6. In combination, side cover members; rods on the side members; threaded studs 50 adapted to receive a pack of loose leaves and detachably pivotally connected to said members; compressing members loosely received on said studs for engagement with

the pack; and nuts on said studs for causing said compressing members to clamp the 55 leaves; the studs being detachable at one end for permitting the leaves to be removed while the nuts are still on the other end.

7. In combination, side members; threaded studs adapted to receive a pack of loose 60 leaves and detachably connected to said members; and nuts received on said studs between said pack and the detachable connections and retainable on the stud during and after detachment of the stud.

8. In combination, side members; threaded studs adapted to receive a pack of loose leaves and detachably pivotally connected to said members; and compressing members received on said studs and clamping said 70 pack.

9. In combination, side members; studs adapted to receive loose leaves and detachably pivotally connected to said members; and compressing members adjustably received on said studs on both sides of the 75 leaves between said leaves and the pivotal connection for clamping the leaves.

10. In combination, side members; threaded studs adapted to receive loose leaves 80 and detachably pivotally connected to said members; and nuts received on said studs on both sides of the leaves between said leaves and the pivotal connections, whereby when the studs are detached from the side 85 members the leaves are still held compressed on the studs.

11. In combination, side cover members; rods removably secured on the side members; threaded studs adapted to receive a 90 pack of loose leaves and provided with transverse end holes pivotally received on said rods; compressing members loosely received on said studs for engagement with the leaves; and nuts on said studs between 95 said compressing members and said end holes for causing said compressing members to clamp the leaves; said studs, nuts, compressing members with the pack clamped between being removable in firmly assembled 100 condition from the cover members.

JOSEPH J. SCHULTZ.
